UNITED STATES PATENT OFFICE.

PATRICK J. FANT, OF HUGO, OKLAHOMA.

PEANUT DIGGER.

1,412,305.

Specification of Letters Patent. Patented Apr. 11, 1922.

Application filed August 25, 1920. Serial No. 405,833.

To all whom it may concern:

Be it known that I, PATRICK J. FANT, a citizen of the United States, residing at Hugo, in the county of Choctaw and State 5 of Oklahoma, have invented certain new and useful Improvements in Peanut Diggers, of which the following is a specification, reference being had to the accompanying drawings.

10 This invention relates to certain improvements in peanut diggers, and it is an object of the invention to provide a device of this general character with a novel and improved topping mechanism operating in a manner 15 to readily and effectively sever the growing vines.

The invention consists in the details of construction and in the combination and arrangement of the several parts of my improved peanut digger whereby certain important advantages are attained and the device rendered simpler, less expensive and otherwise more convenient and advantageous for use, as will be hereinafter more 25 fully set forth.

The novel features of my invention will hereinafter be definitely claimed.

In order that my invention may be the better understood, I will now proceed to describe the same with reference to the accompanying drawings, wherein:

Figure 1 is a view in top plan, with portions broken away, of the peanut digger constructed in accordance with an embodiment 35 of my invention.

Figure 2 is a longitudinal vertical sectional view taken through the device as herein set forth.

Figure 3 is an enlarged fragmentary view 40 partly in elevation and partly in section illustrating a connection between one of the side members of the conveyor mechanism and the coacting link.

As disclosed in the accompanying drawings, 1 denotes a supporting axle and mounted upon the opposite extremities thereof are the traction wheels 2 and the axle 1 is adapted to rotate upon the forward advance of the machine. Suitably engaged with the 45 opposite end portions of the axle 1 but inwardly of the wheels 2 are the standing posts or standards 3 tied or connected at their upper end portions by the transversely disposed member 4 and suitably mounted 50 upon the member 4 is the seat structure S.

Rotatably supported by the posts or stand-

ards 3 at a predetermined point above the axle 1 is a transversely disposed shaft 5 provided at one end with a gear 6 in mesh with a gear 7 mounted on the axle 1. The shaft 60 5 also affords a mounting for the end portions of the substantially horizontally disposed and transversely spaced beams 8 having their forward extremities continued by the downwardly directed extensions 9 65 engaged with an axle 10. Pivotedly engaged about vertical axes are the spindles 11 upon which are mounted the steering wheels 12. Extending rearwardly from the spindles 11 are the arms 14 with which is operatively 70 engaged the steering rod 15. Pivotedly engaged with the rod 15 and the axle 10 is a draft pole or tongue 16. Mounted for vertical swinging movement at a predetermined point intermediate their length are the transversely spaced side members or beams 17 75 which are tied or connected adjacent their opposite ends by the spacing rods 18.

Suitably engaged with the lower end portions of the side members or beams 17 is the 80 transversely disposed cutter bar 19 with which coacts the reciprocating sickle 20. Extending outwardly from the lower end portion of one of the side members or beams 17 is a bracket 21 with which is pivotally engaged the heel portion of a bell crank lever B. One of the arms 22 of the lever B is forwardly directed and is operatively engaged with the end portion of the sickle so that upon rotation the second arm 23 of the lever 85 90 B extends inwardly and transversely through a suitable opening 24 produced in the lower portion of the adjacent or coacting member or beam 17. Pivotedly engaged with the inner end portion of the arm 23 is a pitman 25 95 having its opposite end portion engaged with the crank 26 interposed in the shaft 5. By this arrangement it will be perceived that upon rotation of the shaft 5 the desired reciprocation of the sickle 20 is obtained. The 100 cutter bar 19 and the coacting sickle 20 serve as a topping mechanism.

The cutter bar 19 is positioned in the desired relation to the surface of the ground over which the machine is traveling through 105 the medium of the rigid links 27 pivotally engaged with and depending from the forwardly directed rock arms 28 carried by the transversely disposed rock shaft 29 rotatably supported by the means 8. The 110 rigid links 27 overlie the side members or beams 17 and are provided with the longi-

tudinally disposed slots 30 through which are directed the outstanding threaded shanks 31 disposed through the slots 32 produced in the side members or beams 17. Coacting with the threaded shanks 31 are the clamping nuts 33 or the like, holding the same to the links 27.

Immediately adjacent the cutter bar 19 the side members or beams 17 rotatably support the transversely disposed roller 34. Directed around the roller 34 is an endless conveyor belt 35 preferably of canvas and which belt 35 is also disposed around a transversely disposed roller 36 rotatably supported by the upper or rear end portions of the members or beams 17. The second or upper roller 36 is provided with an extended shaft 37 to which is suitably secured a sprocket 38. Engaged with the sprocket 38 is a chain 39 also directed around a sprocket 40 fixed to an end portion of the shaft 5 whereby it will be perceived that upon forward travel of my improved machine, the upper stretch of the belt 35 will travel upwardly and rearwardly. The vines severed by the topping mechanism carried by the forward end portions of the members or beams 17 are received by the upper stretch of the belt 35 and are discharged within a receptacle or basket supported by the rear portions of the members or beams 17.

From the foregoing description it is thought to be obvious that a peanut digger constructed in accordance with my invention is particularly well adapted for use by reason of the convenience and facility with which it may be assembled and operated, and it will also be obvious that my invention is susceptible of some change and modification without departing from the principles and spirit thereof and for this reason I do not

wish to be understood as limiting myself to the precise arrangement and formation of the several parts herein shown in carrying out my invention in practice except as hereinafter claimed.

I claim:

1. A machine of the character described comprising side members, an endless apron supported by said side members, a shaft serving as a support for the side members, and operatively engaged with the apron for imparting movement thereto, a reciprocating cutter carried by the extremities of the side members adjacent the receiving end of the apron, and an operative connection between the reciprocating cutter and the shaft for operating the cutter.

2. A machine of the character described comprising side members, an endless apron supported by said side members, a shaft serving as a support for the side members and operatively engaged with the apron for imparting movement thereto, a reciprocating cutter carried by the extremities of the side members adjacent the receiving end of the apron, a bell crank lever supported for rocking movement by one of the side members of the conveyor mechanism, one of the arms of the bell crank lever being operatively connected with the reciprocating cutter, the side member supporting the bell crank lever being provided with an opening through which the second arm of the bell crank lever extends, the shaft between the side members being provided with a crank, and a pitman engaged with the crank and with the end portion of the arm of the bell crank lever extending through the opening in the side member.

In testimony whereof I hereunto affix my signature.

PATRICK J. FANT.
